UNITED STATES PATENT OFFICE.

HARRY G. REUSTLE AND WILLIAM W. CANNON, OF CAMDEN, NEW JERSEY; SAID CANNON ASSIGNOR TO SAID REUSTLE.

MACHINE FOR USE IN ASSORTING BUTTONS.

1,303,594.

Specification of Letters Patent. Patented May 13, 1919.

Application filed April 9, 1918. Serial No. 227,530.

To all whom it may concern:

Be it known that we, HARRY G. REUSTLE and WILLIAM W. CANNON, citizens of the United States, residing at Camden, in the county of Camden and State of New Jersey, have invented certain new and useful Improvements in Machines for Use in Assorting Buttons, of which the following is a specification.

10 This invention is a machine for use in assorting buttons and facilitating the separation of the perfect buttons from those which may be discolored or otherwise of doubtful or no marketable value. The invention seeks to provide a machine in which pearl buttons will be delivered upon a table which will carry the buttons past the operator or observer and permit the discolored buttons to be removed, the good buttons being subsequently automatically discharged. The invention also seeks to provide a device which may be easily controlled and in which the delivery of buttons to the inspection table may be regulated as may be desired.

15 25 The invention is illustrated in the accompanying drawings, in which—

Figure 1 is a view partly in side elevation and partly in section of our improved machine;

30 Fig. 2 is a transverse section taken on the line 2—2 of Fig. 1;

Fig. 3 is a plan view;

Fig. 4 is an end elevation of the rotary drum and the parts adjacent the same;

35 Fig. 5 is a detail section on the line 5—5 of Fig. 1.

In carrying out our invention, we employ a supporting frame which may be of any desired character and is illustrated as consisting of legs or pedestals 1, to the upper ends of which is secured a table having a flat top 2 at its rear portion and at its front portion having a second flat top 3 which is somewhat higher than the first mentioned portion. In the rear wall of this table is provided a bearing 4 and upon the under side of the table top is provided a depending lug or bearing 5 in which a driving shaft 6 is journaled, said shaft having its rear end projected beyond the rear wall of the table and carrying a loose pulley 7 through which power may be imparted to the driving shaft from any convenient or preferred motor. On the front end of the driving shaft is a pinion 8 which meshes with a large gear

wheel 9 secured upon a short vertical shaft 10 which is journaled in suitable bearings in the table top 3 and in a beam or cross bar 11 within the top. On the upper end of the shaft 10 is secured a disk or table 12 upon the upper side of which is fixed a mirror 13. Between the bearings 4 and 5, a sprocket pinion 14 is secured to the driving shaft and a sprocket chain 15 is trained around said pinion and a similar pinion 16 secured upon a shaft 17 journaled upon suitable bearings at the upper end of an arched support or standard 18 which is secured to and rises from the table 2, as shown. The shaft 17 extends rearwardly from the said standard or support 18 and is formed integral with or otherwise rigidly connected with the front closed end of a drum or revolving hopper 19, the annular wall of which preferably tapers rearwardly. The rear end of this drum or rotary hopper is in the form of a collar or ring 20 which fits rotatably upon a bearing 21 formed at the lower end of a chute 22 which leads from a magazine or supply hopper 23, the rotary drum or hopper 19 being thereby supported for free rotation. In the annular wall of the drum 19 near the front end thereof are discharge openings 24 which are covered more or less by gates 25 slidably mounted in ways 26, provided on the outer surface of the drum, and connected by links 27 with a grooved ring 28 slidably fitted upon the collar or hub 20. A delivery chute 29 is provided below the drum 19 and leads from a basket 30 which is secured to or formed integral with the upper end of such chute and fits around the under part of the drum in spaced relation thereto so as to receive the buttons discharged from the drum. A bracket 31 is secured to the chute 22 near the lower end thereof and to the upper end of the basket 30 so as to rigidly connect the said members and support the said chute, this bracket being suitably shaped to avoid contact with the links 27 as they rotate with the drum. A bracket or arm 32 is also secured to the rear edge of the basket 30 and upon said bracket or arm is pivoted a yoke or shifting lever 33 carrying pins 34 at its upper end which engage the groove of the collar 28 so that if the lever or yoke be swung about its pivot, the collar will be moved rearwardly or forwardly and the gates 25 consequently adjusted to cover or

uncover the openings 24 to the desired extent and thereby regulate the flow of buttons from the drum. An operating rod 35 is pivoted to the lower end of the lever and extends forwardly so that it may be readily grasped by the operator when occasion demands.

An arm or scraper 36 is secured to the standard or support 18 and projects forwardly therefrom over the inspection table and bears closely against the surface or mirror 13 so that as the buttons are carried against said arm by the rotation of the table, they will be scraped therefrom and deposited upon the receiving table 2, from which they may be gathered and prepared for the market.

Mounted upon the driving shaft so as to rotate therewith but free to slide thereon between the rear end of the top of the frame and the pulley 7 is a clutch member 37 carrying clutch pins 38 which are adapted to engage suitable openings or sockets in the web or spokes of the pulley 7, and thereby lock said pulley to the driving shaft so that motion will be imparted to the driving shaft. This clutch member 37 is preferably a disk or collar having a groove in its peripheral surface which groove is engaged by pins 39 carried by a yoke or lever 40 which is pivotally mounted upon the rear wall of the frame and has its lower end pivoted to a controlling rod 41 which extends forwardly through the front plate or wall of the supporting structure. A cam lever or handle 42 is pivoted in a suitable bracket 43 upon the front wall of the supporting frame and has its rear end pivotally attached to the front end of the controlling rod 41, as shown at 44, while a spring 45 is coiled around the controlling rod between a stop 46 thereon and the front wall or plate of the supporting frame so as to tend normally to hold the rod projected rearwardly and thereby maintain the clutch member out of engagement with the driving pulley. When it is desired to throw the machine into operation, the handle 42 is swung about its pivot 47 so as to pull upon the controlling rod against the tension of the spring 45 and thereby actuate the lever or yoke 40 to throw the clutch member 37 into engagement with the driving pulley, whereupon the shaft 6 will be set in motion and the sprocket chain 15 and pinion 8 at once caused to operate. The pinion 8 being in mesh with the gear wheel 9, the shaft 10 will be caused to rotate and the table 12 will follow such rotation so that buttons deposited on the surface of the table 60 will be caused to travel slowly past the observer. The sprocket chain 15 will act directly upon the pinion 16 and shaft 17 to rotate the drum 19, and the buttons which have been previously placed in the magazine 65 or supply hopper 23 and passed by gravity

through the chute 22 into the drum, will escape through the openings 24 into the basket 30 and thence pass through the chute 29 onto the table. As the table will travel very slowly, the observer will have ample time to 70 carefully inspect all the buttons, and, as the surface of the table is a mirror, both sides of the button can be seen at once. The observer will remove the discolored or imperfect buttons and the good buttons will be 75 scraped from the table by the scraper arm 26 and will drop upon the receiving table 2, whence they may be removed at intervals, as will be readily understood.

It will be noted that our machine is very 80 compact in its arrangement and is free from any complicated structure. It may be set up at a low cost and will be found highly efficient in operation for the purpose for which it is designed.

Having thus described the invention, what is claimed as new is:

1. An apparatus for the purpose set forth comprising a support, a drum mounted for rotation upon the support, the ends of the 90 drum being of unequal diameters and the drum being provided with escape openings in its peripheral wall near its larger end, gates mounted on the drum to extend over said openings, and means to adjust the gates 95 longitudinally of the drum and hold them in a set position.

2. An apparatus for the purpose set forth comprising a support, a drum mounted upon the support, the ends of the drum being of 100 unequal diameters and the drum being provided with escape openings in its peripheral wall near its larger end, gates to cover said openings adjustable longitudinally of the drum, means for operating the drum, a stationary basket disposed below the drum in position to receive articles from said escape openings, and a chute leading from said basket to deliver the articles.

3. An apparatus for the purpose set forth 110 comprising a support, a drum mounted for rotation thereon, a magazine, means for delivering articles from the magazine into one end of the drum, the drum being provided with escape openings in its peripheral wall 115 near its opposite end, gates mounted on said wall to extend over said openings, and means for adjusting the gates longitudinally of the drum whereby to wholly or partly uncover said openings.

4. An apparatus for the purpose set forth comprising a magazine, a chute leading from the magazine, a drum having a hollow hub at one end rotatably fitted on the lower end of said chute, means connected with the 125 opposite end of the drum to rotate the same, a basket below and partly inclosing the drum, a chute leading from said basket, and a coupling connecting the basket with said first mentioned chute.

5. An apparatus for the purpose set forth comprising a rotary drum provided with openings in its annular wall, gates slidably mounted on said wall to extend over said 5 openings, a collar slidably mounted upon the drum, connections between said collar and the gates, and means for shifting said collar whereby to operate the gates.
6. In an apparatus for the purpose set forth, the combination of a supporting structure, a driving shaft mounted therein, a clutch member slidably mounted upon the driving shaft and constrained to rotate therewith, a driving pulley loosely mounted 10 upon the shaft and adapted to be engaged by said clutch member, a lever fulcrumed upon the supporting structure and engaging the clutch member, a controlling rod pivoted to said member and extending forwardly 15 therefrom, a handle member pivoted to the front end of said rod and mounted upon the support, a stop upon said rod, and a spring coiled around the rod between the stop and the support and tending normally to hold 20 the clutch member out of engagement with the driving pulley.
7. An apparatus for the purpose set forth comprising a support, a table mounted there- 25
- on for rotation in a horizontal plane, a frusto-conical drum mounted upon the support for rotation in a vertical plane above and at one side of the table, said drum being closed at its larger end and provided with a hollow hub at its smaller end, and having 30 openings in its side adjacent its larger end, means for rotating the drum and the table, a stationary basket mounted upon the support below and partly inclosing the drum, a chute leading from said basket to the table, 35 a magazine, a chute leading from the magazine to the drum and having its lower end forming a bearing fitting within the hollow hub of the drum, a coupling for supporting the second-mentioned chute from the basket, gates slidably mounted on the side of the 40 drum to extend over the openings therein, a collar slidably mounted upon the hub of the drum, links connecting the collar with the respective gates, and means for shifting the collar whereby to cause the gates to partly 45 or wholly cover the openings in the drum. 50

In testimony whereof we affix our signatures.

HARRY G. REUSTLE. [L.S.]
WILLIAM W. CANNON. [L.S.]
